CHAIR

Howard T. Hallowell, Jenkintown, Pa., assignor
to Standard Pressed Steel Co., Jenkintown, Pa.,
a corporation of Pennsylvania

Application May 25, 1932, Serial No. 613,491

1 Claim. (Cl. 155—157)

The object of my invention is to make a chair in a simple and substantial manner and to provide the chair with an adjustable support for a back rest.

5 This object I attain in the following manner, reference being had to the accompanying drawings, in which:

Fig. 1 is a side view of my improved chair;

Fig. 2 is a sectional plan view on the line 2—2,

Fig. 1, showing the chair seat in dotted lines;

Fig. 3 is a rear view of the back rest;

Fig. 4 is a plan view of the back rest;

Fig. 5 is a detached perspective view of the adjustable support for the back rest;

15 Fig. 6 is a side view showing the improved back rest support as applied to a modified form of seat frame; and

Fig. 7 is a plan view of the seat frame shown in Fig. 6.

20 Referring to Figs. 1 and 2 of the drawings, 1 is one type of base of the chair to which my invention is applied, consisting in the present instance of four bent legs, which are welded at their upper ends to a tubular socket 3, into which extends the stem 4 of the seat section. This stem 4 is clamped between two shaped bars 5 and 6 by means of rivets or bolts 7. Each bar has a central semi-circular portion which partially encircles the upper end of the tubular stem, so that when the rivets 7 are applied the stem is rigidly held between the two bars 5 and 6. These shaped bars are bent as shown in Fig. 2 and have ears 8 at their ends, bent horizontally and secured to the under side of the seat 9 by screws 10 or other fastenings.

25 11 is a back rest secured to the heavy bent wire support 12 by means of a clamp bar 13 shaped to partly encircle the rounded surface of the support. Clamp screws 14, on which are wing nuts 15 in the present instance, tightly clamp the back rest into the position to which it is adjusted. The supports are bent rearwardly so that the entire area of the seat can be used without interference, and the long ends 16 extend through openings 17 in the arms 19 of the bars 5 and 6, and the ends of the arms of the support are threaded at 20, and on the threaded portion of the arms are two wing nuts 21 and 22. One of these wing nuts is on one side of the forward arms 19 of the bars and the other wing nut is on the rear side thereof, so that the back rest can be adjusted towards or from the occupant of the seat by turning the wing nuts, and when the back rest is in the proper position to support the back, the nuts are screwed tightly against the arms 19.

of the bars to support the back rest rigidly in position.

While I have shown my invention as applied to a swivel chair, it will be understood that it can be applied to other types of chair frames without departing from the essential features of the invention.

5 Referring to the modification shown in Figs. 6 and 7, 25 is a rectangular base frame made of four strips of metal bent at the ends and welded together to form a complete rectangular frame with beveled corners. 26 are the legs, which are made in the present instance of plates bent to form angle bars, and the upper end of each leg is flattened to fit against the beveled corners of 10 the frame 25, and these flat surfaces are welded to the frame at the corners. 27 are two angle plates which extend transversely above the rectangular base frame 25, and the horizontal portions 28 of these angle plates are secured to the 15 seat section 9a by screws or other fastenings which pass through slots in the said plates. The vertical portions 29 of the angle plates are riveted to perforated plates 30, Fig. 6, the rivets passing through holes in the flanges 29 of the plates 30, 25 and through holes in the angle plates. The plates 30 have a series of perforations 31 near each side and the main frame 1 is slotted at 33 for the passage of screw bolts 32, which extend through one of the perforations at each side of the plate 30. This arrangement allows for vertical adjustment of the seat section and also allows the seat section to be tilted to accommodate the occupant of the chair, and the screw bolts 32 hold the seat in the position to which it is adjusted.

35 This chair is particularly adapted for machine workers and in some types of machines it is desirable to have the seat tilted backwards so as to accommodate the occupant in a comfortable position. The seat can also be tilted forward when desired.

The two rods 16 which support the back rest extend through perforations in the plates 27. The thumb nuts 21 and 22 are adapted to the threaded portions of the rods. One thumb nut 45 21 on each rod is mounted at the outer side of the forward plate 27, and the other nuts 21 are mounted at the inside of said plate. By turning these nuts the back rest can be adjusted to accommodate the occupant of the seat. The rods 50 16 of the back rest are supported at the forward and rear ends of the seat structure, and can be readily adjusted longitudinally and firmly held after adjustment by the two sets of set screws.

I claim:

The combination of a chair seat; a seat frame secured to the underside of the seat, said frame having vertical members near the front and rear of the seat, the members being perforated for the passage of the arms of a back support; a back rest; a U-shaped back support consisting of an upper cross member and two arms spaced apart; a transverse clamp engaging the arms of the support below the cross member; clamp 5 screws for adjustably securing the clamp and back rest to the arms of the support, the lower

portions of the arms of the support being bent to extend horizontally under the seat and freely through the perforations in the back and front members of the seat frame and normal to said front members, the end of each arm being threaded; and nuts on the arms bearing against both sides of the front member of the seat frame, providing forward and rearward adjustment of the back rest in respect to the seat. 5

HOWARD T. HALLOWELL.
